UNITED STATES PATENT OFFICE.

ALBERT J. LA FRANCIS, OF CHICAGO, ILLINOIS.

WOOL-PELT-SCRUBBING MACHINE.

1,191,521.

Specification of Letters Patent. Patented July 18, 1916.

Application filed July 23, 1915. Serial No. 41,522.

To all whom it may concern:

Be it known that I, ALBERT J. LA FRANCIS, a citizen of the United States, and a resident of Chicago, county of Cook, and State of Illinois, have invented certain new and useful Improvements in Wool-Pelt-Scrubbing Machines, of which the following is declared to be a full, clear, and exact description.

This invention relates to machines for scrubbing wool and other pelts, and its principal object is to provide a simple, efficient and practical machine for accomplishing this purpose.

Another object is to provide an improved pelt scrubbing machine, capable of quickly and thoroughly scrubbing the wool and removing the foreign matter.

Other objects and advantages will occur in the course of this specification, and with all of said objects and advantages in view, this invention consists in the several novel features of construction, arrangement and combination of parts hereinafter fully set forth and particularly defined in the appended claims.

The invention is clearly illustrated in the drawings accompanying this specification in which:

Figure 1 is a side elevation of a machine embodying a simple form of the present invention; Fig. 2 is a longitudinal section thereof, partly broken away; Fig. 3 is a plan of the machine with certain parts broken out to illustrate parts that otherwise would be hidden from view; Fig. 4 is a vertical cross section taken on the line 4-4 of Fig. 1; Fig. 5 is a detail, side view of a journal bearing for certain feed rollers; Fig. 6 is a detail, side elevation of a certain journal bearing for the scrubbing cylinders; Fig. 7 is a side view of one of the spray pipes used in the machine; and Fig. 8 is a view, partly in side elevation and partly in longitudinal section, of a modified form of the invention.

Referring to said drawings, and particularly Figs. 1 to 7 inclusive, the reference numeral, 10, designates a vat or tank upon the side walls, 11, of which, is mounted the scrubbing mechanism and driving apparatus therefor. In said vat, 10, is a traveling, endless conveyer, 12, conveniently constructed of transversely extending, spaced, wooden flights or strips, 13, secured to link belts, 14, that are trained around sprocket wheels, 15, mounted upon shafts, 16, which extend out through the side walls, 11, of the vat, and are journaled in bearing boxes, 17, secured to the

outer faces of the side walls, 11. Preferably, the boxes at one end of the vat are in the form of adjustable take-up boxes. One of the shafts, 16, is provided with a sprocket wheel, 18, over which is trained a sprocket chain, 19, which may be driven from any suitable source of power. Tracks, 19^a, are supported in the tank by cross bars, 20, and said tracks are arranged under the upper portion of the chains and support the upper portion of the endless conveyer.

The endless conveyer forms a traveling table, upon the upper portion of which the pelts are laid, and above said table is a plurality of transversely extending, corrugated, feed rollers, 21, which are journaled in bearing boxes, 22, movably mounted in brackets, 23, that are secured to the top of the side walls, 11. Conveniently, said brackets have upwardly extending guide lugs, 24, between which the bearing boxes are guided to move vertically, and coiled compression springs, 25, are provided between the upper faces of said bearing boxes and the upper ends of bolts, 26, which pass through the base of the brackets and bearing boxes, said springs acting to yieldingly hold the corrugated feed rollers in contact with the table or pelts lying thereon. Said feed rollers, 21, are driven to rotate at about the same surface speed as the traveling table, by suitable means, here shown as consisting of an endless chain, 27, trained over sprocket wheels, 28, secured upon the shafts, 29, of the rollers, 21, said sprocket chain passing also around idlers, 30, 31. Conveniently, one of the idlers, 31, is journaled on a shaft mounted in an adjustable take-up box, 32, secured to the side wall, 95 11, of the vat, whereby the excess slack in the chain may be taken up as occasion requires it. The sprocket chain, 27, is also trained around a sprocket wheel, 33, which may be conveniently driven by a pulley, 34, 100 which may be belted to any suitable source of power.

The particular form of drive mechanism for the feed rollers above described, is not necessary to the invention, broadly considered, as any suitable form of gearing may be employed for driving said feed rollers at approximately the same surface speed as the traveling table.

Between the feed rollers, 21, are the scrubbers, here shown as comprising open cylindrical heads, 35, mounted on shafts, 36, journaled in vertically adjustable bearing boxes, 37. Said bearing boxes are secured to up-

right extensions, 38, of the side walls, 11, by bolts, 39, secured in said side walls, and extending up through said extensions and through plates, 40, resting thereon. On the 5 upper ends of said bolts, 39, are nuts, 41, which bear against the upper faces of the bases of the bearing boxes. Cap screws, 42, are threaded in the bases of the bearing boxes, 37, and have conical ends which 10 rest in conical countersinks in the upper faces of the plates, 40. The bearing boxes, 37, may be raised or lowered to adjust the scrubbers with respect to the traveling table, by turning the cap screws, 42, and nuts, 41, 15 in the proper directions.

In the preferred form of the invention, the scrubbers, 35, comprise end heads, 43, and intermediate heads, 44, between which extend blades or vanes, 45, arranged circumferentially around the marginal edges of said heads to form an open cylinder which may, if desired, be turned up to provide an accurate cylindrical face. The blades or vanes may extend obliquely across the cylindrical faces, although this is immaterial, so far as the scope of this invention is concerned. Said scrubbers may be driven by belts (not shown) trained around pulleys, 46, secured upon the ends of the shafts, 36, 20 and in the operation of the machine, said scrubbers are revolved at a very high rate of speed; their lower sides travel in the same direction as that traveled by the endless conveyer.

35 Between the feed rollers and scrubbers are guide rollers, 47, which are journaled upon the side walls, 11, said guide rollers acting to guide the pelts from each scrubber to the feed roller beyond it. Over said feed rollers are placed guards, 48, which are shown as 40 consisting of angle-shaped plates secured to the side walls of the vat and extending therebetween. Said guards are employed to prevent the pelts from being thrown upon the adjacent guide and feed rollers, by the rapidly revolving scrubbers.

Beyond the last scrubber of the series, is a wringer roller, 49, which is mounted upon a shaft, 50, journaled in the bearing boxes, 51, adjustably supported upon the side walls, 11, of the vat. Said wringer roller may comprise a wooden, cylindrical head, 52, around which is secured a layer of felt, 53, covered by a canvas covering, 54. Said 55 wringer roller bears upon the traveling conveyer or pelts lying thereon, and receives its motion therefrom.

Water is supplied to the table and the pelts lying thereon by sprayer pipes, 55, 60 which extend across the table above the feed rollers, and have perforations in their lower sides (see Fig. 7), through which the water may be sprayed upon the pelts lying on the table. Conveniently said pipes may be connected to a main supply pipe, 56, by vertical

pipes, 57, and the main supply pipe may lead to a pump, 58, which also has an intake pipe, 59, leading from the tank.

In operation, the tank is partly filled with cold water, the pump started, and the several rollers are driven in the directions of the arrows. The pelts, b, to be cleaned, are laid one at the time, upon the receiving end, a, of the traveling table, and the latter carries them underneath the feed roller at the 75 receiving end of the machine. From this point the pelt is moved underneath the first revolving scrubber, where water is sprayed upon it and part of the foreign matter is washed out by the rapidly revolving scrubber. This process is continued until the pelt reaches the wringer roller, which 80 partially removes the water from it. It sometimes happens that when the last part of the pelt passes by a scrubber it is violently 85 thrown forward, but the guards, 48, prevent it from being wrapped around the adjacent guide roller or from falling upon the feed roller. The water falling upon the table falls back into the tank and is pumped back 90 into the spraying system, but fresh water is added as occasion requires.

In the modified form shown in Fig. 8, the traveling table or conveyer is in the form of a drum or cylinder, 12^a, mounted on a 95 suitably driven shaft, 16^a, its cylindrical face being formed of transversely extending, spaced slats or strips, 13^a, secured to the sides, 16^b, of the cylinder. The feed rollers, 21^a, scrubbers, 35^a, guide rollers, 47^a, guards, 48^a, water spraying pipes, 55^a, and wringer roller, 49^a, are grouped around the cylindrical face of the drum, as shown in the drawing, and supported by the framework of the machine; adjustable bearings are provided 100 for the shafts of the rollers, as in the preferred form. Below the drum, 12^a, is a vat, 10^a, in front of which is a platform, 60, upon which the operator stands who feeds the pelts into the machine. Above said platform and arranged close to the face of the drum or cylinder, is a stationary table, 61, upon which the pelts may be laid just prior to feeding them between the drum and first feed roller, 21^a. Below the wringer roller, 115 49^a, is a perforated plate or chute, 62, upon which the cleaned pelts fall, and the lower or delivery end of the said chute may be sufficiently above the floor to permit a car or truck to be placed under the delivery end 120 of the chute to receive the pelts as they leave the wringer roller. A water pumping system such as is shown and described, may be employed in connection with this modified form, as well as with the preferred 125 form. In the operation of this modified form of the machine, the operator stands upon the platform, 60, feeds the pelts between the cylindrical face of the drum and the first feed roller, after which they are 130

5 moved forward between the drum, scrubbers and water pipes, where they are cleaned, as in the preferred form, finally passing out between the drum and wringer roller, and 5 lodging upon the inclined chute, 62, from which they fall upon or may be placed upon a car or truck.

10 While I have shown and described the machine as a wool scrubber, it is obvious 10 that it may be used for various analogous purposes, as, for instance, scraping or removing the foreign matter from other skins, from which wool or hair has been removed, or partially removed.

15 More or less variation of the exact details of construction is possible without departing from the spirit of this invention, and I desire, therefore, not to limit myself to the precise forms of construction shown 20 and described, but intend in the following claims to point out all of the invention disclosed herein.

I claim as new and desire to secure by Letters Patent:

25 1. A wool pelt scrubber, comprising in combination a vat, an endless traveling conveyer therein, a rotary feed roller co-acting with said conveyer to feed wool pelts along with the same, a water spraying pipe and a 30 high speed cylindrical wool pelt scrubber adjacent said feed roller.

35 2. The combination of a traveling conveyer, a rotatory spring pressed feed roller thereabove co-acting therewith to feed pelts along with the same, a high speed rotatory cylindrical scrubber adjacent said traveling conveyer and feed roller, a spray pipe adjacent said scrubber, means for supplying water to said spray pipe, and a rotatory 40 wringer roller co-acting with said traveling conveyer to remove water from the pelts.

45 3. The combination of a vat, an endless traveling table therein for receiving the wool pelts to be cleaned, a plurality of corrugated feed rollers above said table and co-acting therewith to feed the pelts along with the top of said table, a plurality of cylindrical scrubbers adjacent said rollers, a plurality of spray pipes adjacent said scrubbers, means 50 for supplying said spray pipes with water, a plurality of guide rollers adjacent the scrubbers, and a wringer roller co-acting with said traveling table to remove water from the pelts after they have been cleaned by the 55 scrubbers.

60 4. In a wool scrubbing machine, the combination of a vat, sprocket wheels mounted therein, an endless conveyer having sprocket chains trained around said sprocket wheels, 60 suitably supported tracks for supporting the upper portion of said conveyer, a plurality of corrugated feed rollers co-acting with said conveyer to feed wool pelts along the

same, a plurality of cylindrical scrubbers mounted adjacent said feed rollers, water 65 spraying pipes located adjacent said scrubbers, and means for supplying water to said pipes.

5. A wool pelt scrubbing machine, comprising the combination of a vat, an endless traveling, endless conveyer therein, a plurality of spring pressed corrugated feed rollers thereabove co-acting therewith to feed wool pelts along with the same, said rollers being spring-pressed toward the conveyer, water 75 spraying pipes and high speed cylindrical wool pelt scrubbers arranged adjacent said feed rollers, and means for adjusting said scrubbers toward and away from said conveyer.

6. In a machine of the class described, the combination of a vat, an endless traveling table therein, rotatory spring pressed feed rollers above the same and co-acting therewith to move the pelts along with the table, 85 water spraying pipes and rotatory high speed cylindrical wool pelt scrubbers located above the table and adjacent the feed rollers, said scrubbers having circumferentially arranged scrubbing blades.

90 7. In a machine of the class described, the combination of a vat, an endless traveling pelt receiving table therein, a plurality of rotatory feed rollers thereabove and spring-pressed upon the same, water spraying pipes 95 and rotatory high speed cylindrical wool pelt scrubbers located above the table adjacent the feed rollers, said scrubbers having circumferentially arranged scrubbing blades, and being adjustable toward and away from 100 the table.

8. In a machine of the class described, the combination of a traveling table, a plurality of rotatory feed rollers thereabove and spring-pressed upon the table, a plurality 105 of rotatory high speed cylindrical pelt scrubbers having circumferentially arranged scrubbing blades, said scrubbers being mounted adjacent said feed rollers, guide rollers between said scrubbers and feed rollers, and guards above said feed and guide rollers.

9. In a machine of the class described, the combination of a vat, a traveling, endless conveyer therein, rotatory spring pressed 115 feed rollers thereabove, and high speed cylindrical scrubbers having circumferentially arranged blades extending obliquely of the axis, said scrubbers being journaled above the conveyer, sprayer pipes adjacent said 120 scrubbers, a pump communicating with said vat and sprayer pipes, and a wringer roller journaled above said conveyer and in frictional contact therewith.

ALBERT J. LA FRANCIS.
